UNITED STATES PATENT OFFICE

LYNN B. CASE, OF HIGHLAND PARK, NEW JERSEY, ASSIGNOR TO JOHN WALDRON CORPORATION, OF NEW BRUNSWICK, NEW JERSEY, A CORPORATION OF NEW JERSEY

TENSION REGULATOR

Original application filed June 11, 1926, Serial No. 115,398. Divided and this application filed June 20, 1928. Serial No. 286,923.

This invention relates to machines for coating web material, such as that shown and described in my co-pending application for U. S. Letters Patent, Serial No. 115,398, filed June 11, 1926, of which the present application is a division.

The present application is directed to means for controlling the amount of braking friction applied to the roll of stock in order to maintain the proper amount of tension on the web as it passes through the machine.

Referring to the single figure of the drawing, one of the side frames of the machine is illustrated at 1, it being understood that a similar frame is located at the opposite side of the machine for providing a suitable support for the elements of the machine.

The web material to be coated is placed upon the machine in the form of a roll α , being rotatably mounted on the side frames, and placed under the control of braking mechanism hereinafter more fully described, and whereby the rotation of the roll α is retarded.

The material passes from the roll α in the form of a web α^1 under a guide roll 2 rotatably mounted on the side frames 1, then over a second guide roll 3, and thereafter passing under a guide roll 4. The web α^1 then passes over a guide roll 6 and under a chilled iron roll 7. Each of said rollers is rotatably mounted in suitable bearings secured to the side frames 1 of the machine.

Parallel to and adjacent the roll 7 is a roll 12 which supports one end of an apron 15, the opposite end of which passes around and is supported by a second roll 16. The apron 15 may be composed of rubber or other suitable material.

Intermediate the rolls 12 and 16 is a coating table 20 over which the apron 15 passes, the web α^1 also passing over the table 20 in contact with the upper surface of the apron 15. The web α^1 passes from the apron 15 onto a perforated belt 21, rotatably supported on rollers 23 and 24 suitably mounted on the frames 1.

Intermediate the rolls 23 and 24 is a vacuum box 25 which produces a suction through the perforations of that portion of the belt 21 immediately overlying the vacuum box 25.

The web α^1 , in passing from the apron 15, lies in contact with the upper run of the belt 21, and by means of the vacuum box 25 is maintained in substantially rigid contact with the belt 21.

The coating material is applied to the web α^1 immediately adjacent the roll 7 by means of a revolving brush 26, the brush 26 receiving a supply of coating material from a tank 27 by means of a color roll 28 which is maintained at a position partially submerged in the material within the tank 27, and in contact with the brush 26.

Initial spreading of the coating material is effected by means of a stationary brush 29 adjustably mounted on the side frames 1, and immediately overlying one end of the coating table 20 and in contact with the web of material as it passes over the roll 7 and onto the apron 15.

Uniform distribution of the coating material is accomplished by means of a series of batteries of vibrating brushes illustrated at 30, 31 and 32. The operation of the elements of the machine is described in the above mentioned copending application, and therefore will not be reiterated in this application.

A pulley 100 is secured to a shaft 101 rotatably mounted in bearings on the main frames of the machine, and is adapted to supply power to the perforated belt 21 for drawing the web α^1 through the machine. Secured to the shaft 101 is a sprocket wheel 102 connected by means of a sprocket chain 103 with a sprocket 104 secured to a shaft 18, from which the belt 15 is driven by means of a second sprocket wheel 105 connected by a sprocket chain 106 with a sprocket 107 secured to one of the trunnions of the roller 23, whereby the perforated belt 21 is driven.

In order to maintain a definite and proper working tension on the web of material as it passes through the machine I provide a special mounting for the roll α of the material. The roll is provided with a shaft 125 rotatably mounted in bearings 126 at the respective ends thereof, each bearing being secured to a beam 127 mounted on the main frames 1, 1, respectively, by means of roller bearings 128, 128. A brake drum 129 is se-

cured to one end of the shaft 125 and is operatively engaged and partially encircled by a brake band 130, one end of which is adjustably secured to the adjacent beam 127, the other end thereof being pivoted to one leg of a bell crank lever 131 pivoted at 132 to the said beam 127. The other leg 133 of the bell crank lever is in the form of a wedge and is adapted to have its angular side engaged by a roller 134 rotatably mounted on the frame 1. The opposite end of each of the beams 127 is provided with a gear rack 135, meshing with a pinion 136, secured to a shaft 137 rotatably mounted in the frames 1, 1. A plain faced wheel 138 is secured to the shaft 137 and has one end of a strap 139 secured thereto, the strap passing around a pulley 140 and having an adjustable weight, comprising removable discs 141, suspended on its free end.

The weights 141 tend to force the supporting beams 127, 127, with the roll α and the bell crank lever 131 outward, until the bell crank is engaged by the roller 134, the arm 133 thereof being depressed and thereby tightening the brake band 130 on the drum 129, retarding the rotation of the roll α and applying tension to the web α^1 . As the tension becomes abnormal the entire structure of beams, bell crank and roll are moved inward against the action of the weight by the pull of the web α^1 , and the brake band 130 is released to a certain extent from the drum 129, permitting further but restricted unwinding of the material from the roll α .

Having described one embodiment of my invention in detail, various modifications thereto will inevitably present themselves to one familiar with the mechanical arts, therefore, only such limitations should be placed upon the scope of the invention as are prescribed by the appended claims, or dictated by the prior art of record.

I claim:

1. In a machine for handling web material; a stationary frame; means for drawing a web of material from a stock supply; means for automatically maintaining the web under uniform tension, comprising a movable frame adapted to be moved in one direction by the pull of the material; means on the movable frame for retarding the delivery of said web from the said stock supply; means on the stationary frame for operating the retarding means; and means for moving the movable frame in the opposite direction to counterbalance the effect of the pull on the material and to cause actuation of the retarding means on the movable frame, by the operating means on the stationary frame.

2. In a machine for handling web material; a stationary frame; means for drawing a web of material continuously through the machine from a stock supply; means for automatically maintaining the web under

uniform tension, while passing through the machine, comprising a movably supported frame adapted to support said stock supply, said movable frame being adapted to be moved in one direction by the pull of the material; means on the movable frame for retarding the delivery of said web from the said stock supply; means on the stationary frame for operating the retarding means; and means for moving the movable frame in the opposite direction to counterbalance the effect of the pull on the material and to cause actuation of the retarding means on the movable frame, by the operating means on the stationary frame.

3. In a machine for handling web material; a stationary frame; means for drawing a web of material continuously through the machine from a stock supply in the form of a roll; means for automatically maintaining the web under uniform tension while passing through the machine, comprising a movably supported frame adapted to revolvably support said roll, said frame and said roll being adapted to move in one direction by the pull of the material; means on the movable frame for retarding the rotation of the roll; means on the stationary frame for operating the retarding means; and means for moving the movable frame and the roll in the opposite direction to counterbalance the effect of the pull on the material and to cause actuation of the retarding means on the movable frame, by the operating means on the stationary frame.

4. In a machine for coating web material, comprising a stationary frame; means for drawing a web of material continuously through the machine from a stock supply in the form of a roll; means for automatically maintaining the web under uniform tension, while passing through the machine, comprising a movably supported frame adapted to revolvably support said roll, said frame and said roll being adapted to move in one direction by the pull of the material; means for retarding the rotation of the roll on the movable frame; means for operating the retarding means on the stationary frame; and means for moving the movable frame and the roll in the opposite direction to counterbalance the effect of the pull on the material and to cause actuation of the retarding means on the movable frame, by the operating means on the stationary frame.

5. In a machine for coating web material, comprising a stationary frame; means for drawing a web of material continuously through the machine from a stock roll; means for automatically maintaining the web under uniform tension, while passing through the machine, comprising a movably supported frame adapted to revolvably support said roll, said frame and said roll being adapted to move in one direction by the pull of the

- material; a brake on the movable frame for retarding the rotation of the roll; a lever for operating said brake; a projection on the stationary frame adapted to engage and operate said lever; and means for moving 5 the movable frame and the roll in the opposite direction to counterbalance the effect of the pull on the material and to cause actuation of the brake operating lever on the movable frame, by the operating projection on the stationary frame.
6. In a machine for coating web material, comprising a stationary frame; means for drawing a web of material continuously through the machine from a stock roll; means for automatically maintaining the web under uniform tension, while passing through the machine, comprising a movably supported frame adapted to revolvably support said roll, said frame and said roll being adapted 10 to move in one direction by the pull of the material; a brake on the movable frame for retarding the rotation of the roll; a lever for operating said brake; a roller on the stationary frame adapted to be engaged by said lever; and means for moving the movable frame and the roll in the opposite direction to counterbalance the effect of the pull on the material and to cause actuation of the 15 brake operating lever on the movable frame, by the operating roller on the stationary frame.
7. In a machine for coating web material provided with a rigid frame, the combination of means for drawing a web of material continuously through the machine from a roll of stock; a supporting shaft for said roll; a brake drum on said shaft; a frame movably supported on said rigid frame; anti-friction bearings between the movable 20 frame and the rigid frame; bearings on said movable frame for said roll shaft; a bell crank pivoted to said movable frame; a brake band engaging said brake drum and having one end secured to said movable frame and the opposite end secured to one arm of said bell crank; an arm on said bell crank and having an angularly disposed side; a roller, on said rigid frame, adapted to engage the angular side of said arm; means for moving said movable frame and its associated elements in a counter direction to the direction of travel of the web, as it is drawn from the roll, comprising a gear rack on said movable frame; a gear meshing with said rack; a shaft rotatably mounted on said rigid frame and on which said gear is secured; a wheel secured to said gear shaft; a flexible element on the periphery of said wheel and having one end secured thereto; and a weight secured to the free end of said flexible element.

8. In a machine for coating web material provided with a rigid frame, the combination of means for drawing a web of material continuously through the machine from a roll of stock; a supporting shaft for said roll; a brake drum on said shaft; a frame movably supported on said rigid frame; anti-friction bearings between the movable frame and the rigid frame; bearings on said movable frame for said roll shaft; a bell crank pivoted to said movable
